THREAD PROTECTOR

Harold E. McCrery, Apollo, Pa.

Application May 15, 1930. Serial No. 452,589

5 Claims. (Cl. 137—91)

My invention consists of an improvement in thread protectors for the threaded ends of pipe, tubing, rods, etc., and has for one of its objects an improved form of protector of simple construction capable of being inexpensively manufactured and easily applied to the threads to be protected.

It is well recognized by those skilled in the art that protectors of the general character herein contemplated are ordinarily used but once, they being applied to the threads to be protected at the source of supply and then thrown away at the point of use.

While a number of different types of thread protectors have heretofore been proposed, all of those which have come into commercial use, so far as I am aware, have been formed of comparatively heavy metal, usually of such construction as to provide an intermediate portion or portions adapted to cooperate with the threads to be protected, and other portions extending outwardly therefrom. Not infrequently the outwardly extending portions have been such as to present comparatively sharp edges which have not only accumulated dirt and the like which is thereby held in contact with the threads and causes rusting thereof, but such portions have also frequently resulted either in injury to the cars in which the protected pipe was loaded, due to the longitudinal movement of the pipe, or injury to the laborers during the handling thereof.

Protectors of the general character referred to have also been objectionable for the reason that, particularly in the larger sizes, they have represented a considerable item of expense by reason of their initial cost, and have added appreciably to the weight of the articles to which they have been applied.

In accordance with the present invention, I provide a thread protector adapted to effectively protect the threads to which it is applied, and yet which is made out of material of such light gauge, so that the initial cost is decreased, the weight decreased, and manufacture facilitated.

The present protector is also characterized by a shape such that it does not dig into material with which it is in engagement, and which does not serve to collect or retain dirt or other foreign material in contact with the threads.

In the accompanying drawing I have shown for purposes of illustration only certain preferred embodiments of the invention.

In the drawing, Figure 1 is a longitudinal sectional view through a protecting sleeve prior to the assembly therewith of an end ring;

Figure 2 is a view similar to Figure 1 illustrating an end ring and sleeve in cooperative relationship ready for an assembling operation;

Figure 3 is a view similar to Figure 2 illustrating the sleeve and end ring in assembled relationship;

Figure 4 is a vertical sectional view through a piece of pipe having a protector as illustrated in Figure 3 in position thereon; and

Figure 5 is a view similar to Figure 4 illustrating a slightly modified embodiment of the invention.

In accordance with the present invention, I preferably form, by any well known method of manufacture, a section of light gauge tubing which is subsequently cut into lengths to provide a plurality of sleeves 2 as illustrated more particularly in Figure 1 of the drawing. The lengths having been cut off, they will preferably be subjected to a suitable shaping operation, either in a die or otherwise, to provide a bead or other rounded reinforcing and wear resisting terminal portion 3 which may or may not be formed upwardly around a core 4 of wire or the like.

During the shaping operation, the opposite end of the sleeve will preferably be subjected to a shaping operation to provide inturned portions 5, the amount of inturning being such that with the body of the sleeve 2 in contact with the tops of the threads to be protected, as illustrated, for example, in Figure 4 of the drawing, the inturned portions 5 will be in engagement with the root of one or more of the threads. Prior to, simultaneously with or subsequently to the inturning operation, the upper end portion of each of the sleeves may be subjected to a slitting operation to provide a plurality of slits 6 preferably only of such length as to extend through the inturned portion and thereby afford a plurality of spring tongues or fingers. If desired, however, the slitting operation may be omitted and the inturned portion left as a continuous annular inwardly projecting flange.

The sleeves 2 having been formed in the manner referred to, end rings 7 each comprising an outwardly curved portion 8 and a substantially tubular skirt portion 9 are formed, one of the end rings being slipped over the upper end of each of the sleeves in the manner indicated for example in Figure 2 of the drawing. This assembly having been effected, the sleeve and end ring are subjected to a simultaneous shaping operation effective for interlocking the parts. This may be accomplished, for example, by a spinning op-

eration effective for providing an outwardly extending bead 10. This having been accomplished, the protector is ready for use.

In applying the protector to the end of a pipe, 5 rod or the like, it is merely slipped over the end and then lightly tapped, the application being effected entirely by a movement of the protector axially of the threaded article to which it is applied. During this application the spring tongues 10 or fingers constituting the inturned portion 5 of the sleeve 2 spring outwardly over the successive threads until such time that the overhanging lip 11 on the end ring 7 comes into contact with the end of the article. Thereupon further axial 15 movement of the protector is prevented, and the spring fingers snap inwardly into locking engagement with the threads. By properly selecting the thickness of the material relative to the thread characteristics and pipe, there may be 20 provided spring fingers which will more or less tightly engage the threads, thereby eliminating the necessity of subjecting the spring or clip portion of the protector to any special shaping operation such as to cause it to more effectively 25 engage the threads.

In case of the non-slotted construction as previously referred to, it will be obvious that it will depend entirely upon the resiliency of the metal as to whether the protector can be snapped into 30 position in the manner described or not. With relatively light gauge metal, such a snap-on operation may be possible. With relatively heavier material, however, the resiliency of the inturned flange may not be sufficient to permit an application 35 in the manner described, thereby making it necessary to thread the entire protector into position. With the flange disposed at an angle as described for example in connection with Figure 5 of the drawing, such a threading operation 40 may easily be resorted to.

If desired, the end ring may be provided with any number of openings 12 in the outwardly curved portion thereof to permit drainage therefrom of any moisture which may accumulate 45 therein.

In Figures 1 to 4 of the drawing, I have illustrated a protector in which the inturned portion 5 lies in a plane which is substantially normal to the axis of the sleeve 2. In Figure 5, however, 50 I have illustrated a slightly modified embodiment of my invention in which the shaping operation to which the sleeves 2' are subjected is such that the upper end extends at an angle generally corresponding to the angle of the threads to which 55 the protector is to be applied. When so shaped, it will be understood that the inturned portion 5' extends at a similar angle, such that when the protector is applied all parts of the inturned portion will engage a common thread, all portions 60 having similar engaging characteristics and all being equally effective.

If desired, the sleeve and end ring after having been assembled, may be subjected to a suitable operation such, for example, as a spot welding 65 operation to permanently secure the parts together and prevent any possible relative rotative movement therebetween such as might occur, for example, in case of an attempt to remove the protector by engaging only the end ring. The 70 end ring will also preferably be of heavier gauge material than the sleeve, not only for effectively reinforcing the sleeve, but for providing a sufficient cross sectional area of the metal to prevent distortion during handling. Since the in- 75 turned portion 11 of the end ring extends over

the end of the threaded article, it effectively prevents dirt and the like from working inwardly between the protector and the article. The outwardly bulged portion 8 of the end ring, together with the curved end portion 3 of the sleeve provide smooth surfaces on which a pipe or other article is supported so that endwise movement thereof does not chew up or destroy the supporting surface, and such that an operator may grasp the same without fear of injury to himself.

Also, since the main body of the sleeve engages the thread throughout substantially the entire length of such body, there is not provided any recess or pocket in which dirt may accumulate in contact with the threads. This is decidedly advantageous as will be readily appreciated. Since all of this portion of the sleeve is in more or less intimate contact with the threads, a continuous support for the main body of the sleeve is provided, thereby making it possible to use 95 metal of extremely light gauge.

Certain advantages of the present invention arise from the provision of a thread protector comprising a tubular body portion constituting a sleeve and preferably formed of relatively light 100 gauge material in combination with an end ring secured thereto, and preferably of relatively heavier material.

Other advantages of the invention reside in the provision of a protector comprising a sleeve and 105 end ring interlocked one with the other and in which both the sleeve and end ring provide outwardly projecting curved supporting faces.

Still other advantages arise from a structure of the character referred to in which one end 110 of the sleeve is so shaped as to provide a plurality of spring fingers or clips adapted to permit axial movement of the protector during application and insuring a firm interlock with the threads upon conclusion of the axial movement. I have 115 also found it to be desirable to so assemble the sleeves and end rings that the clip portions of the protectors are in turn protected by the end rings.

Where the clip portions lie in a substantially 120 common plane, they do not afford as effective a thread engaging means as where they are shaped to extend at the angle of the thread, but in either case the spring characteristics are such as to afford such an interlock with the threads as 125 to prevent accidental loosening of the protector and require a relative rotative movement in order to remove the same.

While I have herein illustrated and described certain preferred embodiments of the present 130 invention, together with the preferred means of making the same, it will be understood that changes in both the method and in the construction of the parts may be made without departing either from the spirit of the invention or the 135 scope of my broader claims.

I claim:

1. An article of manufacture, a thread protector comprising a sleeve having an outwardly curved lower end and an inturned upper end, and 140 an end ring secured to the upper end of the sleeve and inclosing said inturned portion, said inturned portion being formed with a plurality of slits to provide spring fingers.

2. An article of manufacture, a thread protector comprising a sleeve having an inturned upper end, and an end ring secured to the upper end of the sleeve and enclosing said inturned portion, said inturned portion being formed with a 145 plurality of slits to provide spring fingers.

3. As an article of manufacture, a thread protector comprising a sleeve having an inturned upper end, said inturned upper end being formed with a plurality of slits to provide spring fingers, 5 and an end ring secured to the upper end of the sleeve and enclosing said inturned portion, said end ring being adapted to extend over the upper end of the pipe member.

4. As an article of manufacture, a thread protector comprising a sleeve having an inturned upper end, said inturned upper end being formed with a plurality of slits to provide spring fingers, 10 and an end ring secured to the upper end of the sleeve and enclosing said inturned portion, said end ring being adapted to extend over the upper end of the pipe member and having a roll portion

between the point of engagement with the end of the pipe member and the point where it is secured to the sleeve.

5. As an article of manufacture, a thread protector comprising a sleeve adapted to lie alongside the threads of a pipe member, said sleeve having an inturned upper end adapted to engage the threads of a pipe member and an end ring engaging the upper end of the sleeve adapted to extend over the end of the pipe member, and being adapted to exert a pressure on the upper end of the sleeve for bringing the inturned upper end thereof into tighter engagement with the threads of the pipe member by pressure of the pipe member on the ring. 80
